UNITED STATES PATENT OFFICE.

STANLEY ALDER, OF SUNDERLAND, ENGLAND.

EXPLOSION-ENGINE.

1,233,951.

Specification of Letters Patent.

Patented July 17, 1917.

Application filed July 31, 1915. Serial No. 42,995.

To all whom it may concern:

Be it known that I, STANLEY ALDER, subject of the King of Great Britain, residing at 78 Dundas street, Sunderland, in the county of Durham, England, have invented certain new and useful Improvements in Explosion-Engines, of which the following is a specification.

The invention relates to an explosion engine, and provides therein and therewith a combination of parts efficiently utilizing the exhaust gases and some of the heated water in the water jacket for low pressure steam production in a steam generator arranged to externally surround the jacket containing the cooling water. A combination of parts includes a steam engine incorporated as a part working with the explosion engine and operated by steam supplied from the generator aforesaid, surrounding the jacket containing the cooling water, and, further, combines with the explosion engine means whereby wet steam from the generator is supplied to the explosion engine to enrich the mixture and aid internal cooling and expansion. A further combined feature in the engine is a vacuum jacket surrounding the steam generator and steam engine either wholly or in part to prevent external radiation.

The improvements are diagrammatically illustrated by the accompanying drawing showing in vertical section a simple application of the combined features aforesaid applied to an engine of two-stroke cycle.

The explosion cylinder and piston are represented at *a* and *c*, and the water jacket surrounding said cylinder and part of the valve pockets at *d*. The cooling water is suitably forced into the jacket *d* through the supply passage *d*², and leaves said jacket mainly through the outlet *d*³, in connection with which outlet is provided a suitable throttle *d*⁰ for producing a back pressure on the outflow of the cooling water to permit of the cooling water in said jacket *d* being heated to the highest possible temperature consistent with the efficient working of the explosion engine. *d*⁴ and *d*⁵ are gas and air admission valves to the explosion cylinder *a*, and *e* is an admission valve for wet steam into said cylinder, each valve being mechanically operated to open in suitable and known manners.

The steam valve *e* controls the admission to the cylinder, *a*, of steam raised in a

steam generator, *f*, provided to surround the water jacket and parts of the pockets of the valves *d*⁴ *d*⁵. Communication between said steam generator *f* and the valve *e* is at 60 *f*². Arranged within the steam generator *f* is a series of circulating pipes *g*, communicating with the exhaust ports, *g*², from the explosion cylinder, *a*, and with the outlet *g*³ for the exhaust gases to the atmosphere, or 65 passage leading thereto. The exhaust gases pass through the various exhaust ports *g*² into the circulating pipes *g*, and the heat thereof is utilized in the steam generator *f* for steam production. The whole of the 70 pipes *g* discharge into the common exhaust outlet *g*³.

The steam generator *f* is substantially inclosed within a vacuum jacket *h* exhausted by a mercury or other suitable arrangement 75 of pump, for the purpose of preventing radiation of heat from the generator *f*.

For the generation of steam the generator is supplied with the hottest water leaving the water jacket *d* by the pump *i* and valve 80 *j*. The pipe *i*² conducts water through the non-return valve *j*² to the pump *i*, and the pipe *i*³ conducts said water from the pump through the non-return valve *j*³ 85 to the generator *f*.

The pump *i* is driven from the crank shaft *x* of the engine through a set of eccentrics *y*, which are reversing eccentrics, the plunger *i*⁴ of the pump being suitably connected with the eccentrics' gear. 90

This gear is mainly for the operation of a slide valve *l* working within a steam chest *l*². Said steam chest is supplied with steam from the generator *f* by a pipe *l*³. The slide valve *l* controls inlet and exhaust ports *m* *n* 95 of a steam cylinder *o* arranged concentric with the explosion cylinder *a* and within the vacuum jacket *h*, and fitted with a large diameter piston *o*² reciprocating as one piece with the explosion piston *c*, to thereby incorporate with the explosion engine a steam engine. 100

By such combination of parts the hottest water in the cooling jacket, and the heat in the exhaust gases, are utilized in a steam generator inclosing the water jacket for the purpose of raising steam to be used as part of the explosive charge, if desired, to enrich the mixture and aid internal cooling and expansion of the exhaust gases, and as the motive power in a steam engine incorporated 110 with the explosion engine.

The reversing eccentrics γ and the link motion gear thereof are constructed and arranged to operate in a manner well known in connection with engines such as a marine steam engine.

The reversing cams for actuating valves e , d^4 and d^5 are constructed to operate in a manner well known in connection with engines of the "Diesel" type and are operated for the purpose of reversing simultaneously and in conjunction with the reversing eccentrics γ on the crank shaft, so that at the instant the slide valve l is reversed so also are the valves e , d^4 and d^5 .

Having now described my invention what I claim and desire to secure by Letters Patent is:—

1. The combination with an explosion engine having a water cooling jacket, of a non-communicating steam generator surrounding said jacket, means arranged within said generator and connected to receive exhaust gases from the engine and to circulate the same within said generator for steam production therein, and means connected to receive heated water from said cooling jacket and operative to introduce such water into said steam generator.

2. The combination with an explosion engine having a water cooling jacket, of a steam generator surrounding said jacket but non-communicating relatively thereto, means arranged within said generator and connected to receive exhaust gases from the engine and to circulate such gases within the generator for steam production therein, means connected to receive heated water from the cooling jacket and to introduce the same in the steam generator, and a steam engine incorporated as a part working with

the explosion engine and operative by steam supplied thereto from said generator.

3. The combination with an explosion engine having a water cooling jacket, of a steam generator surrounding said jacket but non-communicating relatively thereto, means arranged within said generator and connected to receive exhaust gases from the engine and to circulate the same within the generator for steam production thereon, means connected to receive heated water from the jacket and operative to force the same into said generator, a steam engine incorporated as a part working with the explosion engine and operative by steam supplied thereto from the steam generator, and means for supplying steam from the generator to the explosion engine as part of the charge thereof.

4. The combination with an explosion engine having a water cooling jacket, of a steam generator surrounding said jacket but non-communicating relatively thereto, means arranged within the generator and connected to receive exhaust gases from the engine and to circulate the same within the generator for steam production therein, means connected to receive heated water from the cooling jacket and operative to introduce the same into the steam generator, and a vacuum jacket arranged externally of the explosion cylinder, steam cylinder, and generator to prevent radiation.

In testimony whereof I have hereunto set my hand in presence of two subscribing witnesses.

STANLEY ALDER.
